COIN CONTROLLED MECHANISM

Francis C. Du Grenier, Haverhill, Mass., assignor
to Blanche E. Bouchard, Haverhill, Mass.

Application February 5, 1935, Serial No. 5,009

6 Claims. (Cl. 194—93)

This invention relates to coin controlled apparatus for vending machines, and more particularly to mechanism of the type which acts to release the dispensing mechanism when a plurality of coins have been inserted, the denominations of which are equal to a certain amount, as, for example, three nickels, or a nickel and a dime.

The objects of my invention are to provide a simple and effective coin controlled releasing mechanism, in which the dispensing mechanism will be released when three nickels, or when one nickel and a dime have been placed therein, and in which, if one nickel and a dime have been placed therein and then an additional nickel is inserted, the latter will immediately be returned, or if two or three nickels have been inserted and then a dime is inserted, the nickels in excess of one will be returned. Also to provide means whereby, if an attempt is made to have the coins restored after the dispensing operation has been advanced sufficiently to release the same, such attempts will be frustrated and the dispensing operation will have to be continued, so that the coins inserted will be retained in the machine.

I accomplish these objects by providing a pair of locking levers, both of which must be held in an inoperative position to permit operation of the dispensing mechanism, one of which is held in its inoperative position by the first nickel inserted, and the other of which is held in its inoperative position either by the third nickel inserted, or by a dime when inserted. Also by providing an auxiliary coin-holding device which is arranged normally to hold the second and third nickel in position, but which is moved to an inoperative position upon the insertion of a dime, so that any nickels which are, or have been inserted, in addition to the first nickel, will be returned if, or when a dime is inserted. Also by providing an auxiliary coin retaining device which is moved into operative position by the dispensing mechanism, when moved initially, and before the coins pass into the receiving chamber, so that, if it is attempted to dislodge the coin retaining means which is controlled by the dime, the attempt will be unsuccessful.

For a more complete and detailed disclosure of my invention, reference is now made to the following specification in connection with the accompanying drawings, in which:

Fig. 1 is a view in elevation of the coin-controlled mechanism embodying my invention, which is mounted on the right hand end of the casing.

Fig. 2 is a sectional view thereof at line 2—2 of Fig. 1.

Figs. 3 and 4 are sectional views at lines 3—3 and 4—4, respectively, of Fig. 1.

Figs. 5 and 8 are views similar to Fig. 4, showing the parts in different positions.

Fig. 6 is a detail sectional view at line 6—6 of Fig. 4.

Fig. 7 is a front elevation of the enclosing cabinet.

Fig. 9 is a detail sectional view at line 9—9 of Fig. 8.

Figs. 10 and 11 are detail views of the two locking levers.

As is customary in machines of this character, the machine proper is enclosed in a cabinet, as 10, at the front of which a series of pull handles 12 protrude, whereby, when any one of them is pulled out, a package will be dispensed from the stack of packages in the rear thereof and delivered to shelf 13. As indicated in Fig. 3, a crank shaft 14 is journaled at its ends in the end frames 15 of the machine, and a finger, as 16, depends from each pull handle and engages the crank portion of shaft 14, so that, when any one of the handles is pulled out, the shaft 14 will be oscillated in the direction of the arrow in Fig. 1, and will be returned to its initial position when the handle is drawn back. The end portion of shaft 14 extends thru the frame 15 and a controlling device or cam 18 is secured thereon, so that the shaft may be rotated sufficiently to permit a dispensing operation only when the cam 18 is free to move therewith.

According to my invention, the particular means employed to lock the shaft against operative movement consists of a pair of locking levers 20 and 22, which are arranged side by side in proximity and mounted on a pivot 24 at their upper ends. Each lever has a friction roll 21, 23 at its lower end, which is arranged in rolling contact with the outer side of cam 18, and coil springs 26, 27 are connected to said levers 20, 22 respectively, and tend to swing the same in the direction to hold the friction rolls thereon in contact with the surface of the cam 18. In the initial position of the parts, projections 28, 30 on cam 18 engage rolls 21, 23, holding springs 26, 27 under tension, as shown in Figs. 1 and 8, but, on a slight forward movement of cam 18, caused by pulling out any one of the handles 12, either, or both levers 20, 22 will be swung inward, so that the rolls 21, 23 thereon will be engaged by abutments 31, 33 on the cam, as shown in Fig. 3, positively locking the machine against further operation by

the handles. Obviously, therefore, to permit a dispensing operation, both levers 20, 22 must be held against movement by their respective springs into a position to which they will be engaged by 5 the abutments on cam 18.

In the present machine all coin detecting operations take place immediately on the insertion of the coins in the machine, and as the present invention in no way relates to any coin detecting 10 operations, means of that character are not shown. In the present instance the machine is designed to be operated to perform the dispensing operation after three nickels, or one nickel and one dime have been inserted, and, after acceptance by the 15 coin testing means, the nickels fall down a passage 34 and the dimes down a passage 35, and the first nickel inserted and the dime come to rest on the top side of a projection, or coin-support 36 formed on the peripheral portion of cam 18, and 20 are retained in this position by a finger 38 on the inner end of a push rod 39, as shown in Figs. 1, 4, 6, 8 and 9, so that, when the handle at the outer end of rod 39 is pushed inward, the coins supported on projection 36 will roll therefrom and fall 25 into the coin return passage 40 and be delivered to the shelf 13. If two additional nickels have been inserted, they will be supported edge to edge on the one first inserted, one above the other, as shown in Fig. 6, so that if the rod 39 is moved 30 inward they will also be restored. Also if more than three nickels are inserted, or more than one dime is inserted, the additional coins will merely strike the top nickel, or the dime and immediately roll into the return passage, as shown 35 in Fig. 6.

As shown in Fig. 9, when the bottom nickel and the dime are held on the support 36 and retained thereon by finger 38, the dime will be held somewhat off center with relation to the nickel, so that 40 it only partly overlaps the same. The lever 20 is provided with a finger 42, which is arranged in position to engage the portion of the nickel which is not overlapped by the dime, when both are sustained on support 36, as shown in Figs. 4, 6, 8 45 and 9, so that when cam 18 is rotated, so that its projection 28 is carried out of engagement with the roll 21, lever 20 will be swung inward by its spring 26 until finger 42 engages the side of the nickel, thereby preventing lever 20 from swinging 50 inward sufficiently to engage abutment 31, and holding the same in the position of Fig. 4, so that, as the cam 18 rotates, the roll 21 may engage the inclined top portion of abutment 31, and may ride upon the outer side of cam 18, and thus will 55 be inoperative to prevent the dispensing operation.

The lever 22 also has a finger 44, which operates in a similar manner to hold lever 22 in an inoperative position by engagement with one side of the third nickel which is inserted, as indicated in Fig. 6, so that when three nickels have been inserted both locking levers will be held in their inoperative positions and the dispensing operation will be permitted.

The lever 22 is also provided with a finger 45, 65 which is arranged in position to engage the dime when held in position on support 36, shown in Figs. 6 and 9, so that if a nickel and a dime have been inserted both locking levers will be held in their inoperative positions, permitting the dispensing operation to be performed, and in all instances when movement of cam 18 is permitted, beyond the point where it would be locked, support 36 is moved from beneath the coins supported thereon, so that they will fall into the money box. 70 As the locking levers 20, 22 press the coins firmly

against the sides of the coin passages, they would not be released when the support 36 is moved from beneath them if this pressure were not removed. The cam 18 is therefore arranged to press the levers out of engagement with the coins after the 5 abutments 31, 33 have been moved past the position at which they may be engaged with said levers, as shown in Fig. 5.

Means are further provided to prevent over payment, as, for example, when three nickels 10 have been inserted and then without operating the machine, a dime is inserted, which consists of a latch, or dog 46, which is arranged to swing freely on a pivot 47 and which is provided with a finger 48 at an intermediate point thereon, which normally extends in a position to engage the edge of the second nickel in the rear thereof, so that, under normal conditions, shown in Figs. 3, 4, and 5, it will hold the nickel in the position of Fig. 6, and prevent the same from falling into the return passage 40, but if withdrawn from this position will permit this nickel, and, if a third nickel is supported thereon, both to pass into the return passage. A finger 50 is formed on the lower end of dog 46 and normally extends into the dime passage 35 a short distance above the point where the dime is held by support 36, the edge of said finger having an inclined face 51, so arranged that it faces upward 20 in position to be engaged by the dime, as it falls into position, thereby causing the dog to be swung to the position of Fig. 8, and, at the same time, withdrawing finger 48 from the position in which it retains the second nickel in its passage, so that, when a dime falls into position, if a second nickel is, or has been inserted, the latter will immediately be restored, and, if a third nickel has been inserted, it will also be restored.

It has been ascertained, however, that, on account of the fact that dog 46 can be moved out 40 of its intercepting position by as slight a force as the impact of a falling dime, it is possible, by subjecting the machine to a somewhat violent jarring action, as by striking it a sharp blow, 45 to cause the dog 46 to be swung back to its inoperative position. This fact is of no consequence if the dispensing operation has not been started, as the second and third nickels will merely be returned and it will not then be possible to operate the machine without returning them, but it is necessary to provide a short period between the point when the cam 18 has been moved to a point where the locking lever will no longer intercept its movement and the point where the 55 coins are dumped from support 36 into the money box, so that if the casing were struck a sharp blow while the cam is held in this position, two of the nickels would fall into the return passage, and then the operator could continue the operation 60 and secure a package for a single nickel.

Machines of this character are usually provided with so-called scavenger means, which operates to liberate and return all defective coins or slugs which have been intercepted by the coin 65 tester.

In the present instance the lever 52 mounted on pivot 53, performs this function, said lever having a roll 54 at its lower end, which engages a cam face on cam 18 and is moved to perform 70 its normal functions, (such means not being shown in the present instance), before the cam 18 is moved to the point where it will be released by levers 20, 22. Said lever 52 is provided with a finger 55 at its upper end, see Figs. 1 and 2, which 75

is inoperative when the parts are in their initial position, but which, immediately on the initial movement of cam 18, is moved inward to a position side by side with finger 48 of dog 46, as indicated in Fig. 6. Consequently if the dog 46 is dislodged in any way after the dispensing operation has been started and before the coins are delivered to the money box, the finger 55 will prevent the discharge of any of the coins into the return passage, so that they will be discharged into the money box.

The above described construction is primarily advantageous on account of the simplicity and durability of its parts and the fact that the action is positive and in no way dependent on the dimensions of the coins which are inserted, the latter having previously been thoroughly tested before they reach the position in which they act to permit operation of the dispensing means.

It will be apparent that the above described mechanism is not limited to use in connection with the particular coins referred to, as various other combinations of coins than those referred to may be employed practically without modification.

I claim:

1. In a coin-controlled dispensing machine having a pair of coin passages for coins of different denominations, means for supporting a coin in one of said passages and for supporting a plurality of coins edge to edge one above another in the other passage, whereby all of said coins will be held in predetermined positions, operating devices movable to perform a dispensing operation including a controlling device which is movable therewith from an initial position, a pair of locking devices arranged to be held in inoperative positions by said controlling device when in its initial position, means to move said locking devices into positions to lock said controlling device when moved from its initial position, means on one of said locking devices arranged to engage the lowermost coin of said plurality of coins, and on the other of said locking devices to engage the top-most coin thereof and the single coin when held in the other passage in said positions, to hold said locking devices in their inoperative positions when the requisite number of coins have been placed in one passage, or a single coin has been placed in both passages, to permit movement of said controlling device beyond the position where it may be locked, so that the dispensing operation may be performed.

2. A coin-controlled dispensing machine having a coin passage and supporting means for holding a coin in a predetermined position thereon, operating devices movable to perform a dispensing operation, a rotatably mounted cam movable from an initial position by said operating devices when moved operatively, a locking device held in an inoperative position by said cam when in its said initial position and having means arranged to move it into position to lock said cam when the latter is moved initially from its said position, and to be engaged with one side of a coin when held in said position to press its opposite side against the side of said passage thereby to hold said locking device against movement to locking position, and means on said cam arranged, when moved beyond a position in which it may be locked, to disengage said locking device from the coin and permit delivery thereof from said supporting means.

3. A coin-controlled dispensing machine having a coin passage and operating devices movable to perform a dispensing operation, a controlling

device movable from an initial position by said operating devices when moved operatively, a support on said controlling device and means for holding a coin delivered to said passage in a predetermined position therein, a locking device, a spring arranged to move said locking device to engage one side of a coin held on said support and to move said device into position to lock said controlling device, means on said controlling device arranged, when in its initial position, to hold said locking device in an inoperative position, and to permit the same to be actuated when the controlling device is moved from initial position, whereby a coin on said support may hold the locking device against movement to its locking position, and means on said controlling device for disengaging said locking device from the coin when it has been moved beyond the position at which it may be locked, said support being arranged to be simultaneously moved from its coin supporting position.

4. In a coin-controlled dispensing machine having a passage for coins of one denomination and means to support a plurality of coins therein edge to edge one above another, and having a second passage for coins of another denomination and means arranged to support a single coin therein, and a coin return passage, operating devices movable to perform a dispensing operation, a controlling device movable from an initial position by said operating devices when moved operatively, locking devices normally held in an inoperative position by said controlling device when in its initial position and having means for moving the same to lock said operating devices on operative movement thereof, means on said locking devices for engagement with the lowermost and the top-most coins in said first named passage and with the coin in the other passage, to hold said locking devices in inoperative position, and a latch having means to prevent the second coin in the first named passage from passing into said return passage, said latch being arranged to be engaged by a coin placed in the other passage and to be moved thereby into position to permit said second coin to pass into said return passage.

5. In a coin-controlled dispensing machine having a passage for coins of one denomination and means to support a plurality of coins therein edge to edge one above another, and having a second passage for coins of another denomination and means arranged to support a single coin therein, and a coin return passage, operating devices movable to perform a dispensing operation, a controlling device movable from an initial position by said operating devices when moved operatively, locking devices normally held in an inoperative position by said controlling device when in its initial position and having means for moving the same to lock said operating devices on operative movement thereof, means on said locking devices for engagement with the lowermost and the top-most coins in said first named passage and with the coin in the other passage, to hold said locking devices in inoperative position, and a pivotally suspended latch having a finger normally extending in position to prevent delivery of the coins above the lowest coin in the first named passage to said return passage and having an inclined face arranged to be engaged by a coin placed in the second named coin passage and to move the latch to a position in which its said finger will be inoperative.

6. In a coin-controlled dispensing machine

having a passage for coins of one denomination and means to support a plurality of coins therein edge to edge one above another, and having a second passage for coins of another denomination and means arranged to support a single coin therein, and a coin return passage, operating devices movable to perform a dispensing operation, a controlling device movable from an initial position by said operating devices when moved operatively, locking devices normally held in an inoperative position by said controlling device when in its initial position and having means for moving the same to lock said operating devices on operative movement thereof, means on said locking devices for engagement with the lowermost

and the top-most coins in said first named passage and with the coin in the other passage, to hold said locking devices in inoperative position, a pivotally suspended latch having a finger normally extending in position to prevent delivery of the coins above the lowest coin in the first named passage to said return passage and having means arranged to be engaged by a coin placed in said second named coin passage to move said latch to withdraw its finger to an inoperative position and normally inoperative means arranged to supplement the action of said finger and movable into operative position by said operating devices on initial movement thereof. 5

FRANCIS C. DU GRENIER. 15
